GUY F. KELLEY, OF BEAUMONT, CALIFORNIA

AIR-CONDITIONING APPARATUS

Application filed February 12, 1930. Serial No. 427,889.

This invention relates to an air conditioning apparatus, the general object of the invention being to provide means for washing and either cooling or heating the air, so that when the air is discharged into a room or other place, the air will be pure and will change the temperature of the room without unduly raising the humidity.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

- 20 Figure 1 is an elevation of the invention.
- Figure 2 is a section on line 2—2 of Figure 1.
- Figure 3 is a section on line 3—3 of Figure 2.
- 25 Figure 4 is a detail view of a baffle plate.
- Figure 5 is a sectional view through one of the exhaust members.
- Figure 6 is a section on line 6—6 of Figure 5.
- 30 In these drawings, the numeral 1 indicates a cylinder supported by the frame 2 and having its inlet end open and its other end closed. The open end has an inwardly extending flange 3 which prevents water from flowing from this end. A fan 4 and its motor 5 are supported by a frame 6 with the fan fitting in the opening formed by the flange 3 so that the fan will force air into the cylinder. The space between the flange and the ring which 35 surrounds the fan is closed by a strip 7 of canvas or the like. This canvas joint confines the air and also acts to prevent the fan contacting the cylinder, thus eliminating noise due to vibrations of the fan and its frame. The fan and motor are enclosed by a frame 8 of wire mesh which is removable and which acts as an accident preventive.
- 45 The air is discharged from the cylinder through the openings 9 formed in the upper part of the closed end of the cylinder into

the conduits 10 which lead the air to the room or other point of use.

As the air passes through the cylinder, it is subjected to the action of a plurality of water sprays from the nozzles 11. These nozzles are arranged in two sets, one on each side of the center of the cylinder. The forward set of nozzles are arranged at the axis of the cylinder and the nozzles of the other set are located above the axis, as shown in Figure 3. The first two nozzles direct the spray into the stream of air in the direction of travel of the air, but all the other nozzles direct the spray against the stream of air. The nozzles are horizontally arranged and are carried by elbows 12 on the vertical pipes 13 and the pipes 13 of each set of nozzles are connected with the horizontal pipe 14 in the lower part of the cylinder, the inner ends of the pipes 14 being connected with the lower ends of the pipes 15 which pass upwardly through the top of the cylinder where they are connected with the supply pipe 16 which is connected with the pump 17 driven from the motor 18.

The water from the sprays will drain from the cylinder through the holes 19 in the bottom thereof, into the trough 20 connected with the bottom of the cylinder and from this trough, the water will pass down the discharge pipe 21, which is detachably connected with the discharge of the trough, into a tank 22 placed under the cylinder. This tank is provided with a trough 23 to which the bottom of the tank slopes and the water must pass through a screen 24 before entering the trough 23. The inlet of the pump is connected with this trough 23 by the pipe 25. Thus the water is used over and over again as the tank catches the water draining from the cylinder and the pump takes the water from the tank and returns it to the sprays. The tank is provided with a level indicator 26, an overflow 27 and water can be supplied to the tank when desired through the supply pipe 28. A drain pipe 29, containing a valve 30, is connected with the discharge pipe of the pump so that the tank can be emptied by the pump when desired. Parts of the cover of the tank are removable, as shown at 31.

The spray heads are of such construction

as to form a fine mist or fog and the first two heads are arranged to direct the spray away from the inlet end of the cylinder so as to not wet the fan. The heads throw the water 5 about one foot before it strikes the walls of the cylinder and in order to prevent noise of the water striking the cylinder and to cool the water, I provide a baffle arrangement for each head which consists of a strip 32 spaced 10 from the cylinder by blocks 33 of rubber and carrying the fins 34, one of which is shown in Figure 4. The fins extend horizontally from the circular strip and are corrugated as shown in Figure 4, so as to guide the water 15 to a more even distribution over their edges.

The extreme ends of the baffles are bolted to the cylinder with rubber insulated bolts and rubber washers passing through quarter inch holes drilled through the cylinder. The 20 fins commence seven inches from the extreme ends of the baffles, the fins are spaced three inches apart and follow directly underneath each other until twelve fins are placed on each side of each baffle. The object of these fins is 25 to cool the sprayed water, for after the water leaves the sprays and strikes against the baffles containing the fins, the water then drips down from one fin to the one beneath it until it finally reaches the bottom of the cylinder, runs out one of the holes in the bottom 30 of the cylinder into the trough underneath the cylinder, down the trough to the four inch diameter pipe which delivers the water back into the water tank underneath the cylinder 35 where it is again sprayed back into the cylinder by means of the water pump. These baffles baffle or diminish the water noise, the fins cool the water to a lower temperature than could be accomplished were the water 40 allowed to cling to and flow around and down the inner sides of the cylinder when finding an outlet to the water tank.

Rectangular openings surrounded by the frames 35 are arranged in the top of the 45 cylinder, the frames being closed by the covers 36 having transparent parts 37. By looking through the transparent portions, one can tell whether or not the sprays are functioning properly and by removing the covers, the 50 parts can be adjusted or cleaned. A lamp 38 is located in the top part of the cylinder so as to illuminate the interior of the same when the parts are to be inspected.

The conduits 10 discharge into the outlet 55 or fan boxes 39, each of which passes through a hole in the wall of the room or other place where the air is to be discharged. A discharge fan 40 is placed in the discharge end of each box and this end of the box is 60 reduced in size to produce greater velocity and less back lash or short circuit of the air thrown out by the fan. The fan is driven from the motor 41 supported by the frame 42 in the box. As the air enters each box, it 65 passes through the baffles 43 which removes

excessive moisture from the air. The baffles are carried by two trays or slides 44, slidably supported in the box so that the trays can be pulled therefrom. The baffles are formed of V-shaped strips vertically arranged, with 70 the strips at each side of the rear tray having their apexes pointing outwardly and those of the front tray pointing inwardly, as shown in Figure 5. The central space formed by the two inner strips of the rear tray is divided into two V-shaped passages by a rectangular member 45 and two such members 46 are placed at the center of the front tray. Thus the air is first caused to 75 flow toward the sides of the box as it strikes the rear portions of the baffles of the rear tray and then caused to flow toward the center of the box as it strikes the front portions of said baffles. The rear portions of the baffles of the front tray cause the air to 80 continue in the same direction and finally the front portions of the baffles of the front tray direct the air toward the sides of the box.

After passing the baffles, the air is acted 90 on by the refrigerating coils 47. The coils in the boxes are arranged in series, as shown in Figures 2 and 6, with the inlet end of each set of coils arranged at the center, as shown in Figures 5 and 6.

The baffles dry and control the direction of the washed and cooled air passing through them, the refrigerant coil next cools the air to a lower temperature and at the same time removes any remaining small particles of 100 moisture by forming this moisture into frost on the coils. The water caught by these baffles, as well as the drip from the refrigerant coils finds a natural drain back into the water tank by way of first the ducts, then through the cooling cylinder and then into the water tank. The baffles can easily be removed from the fan boxes as each fan box is provided with a sliding door for this purpose.

It might be well at this point to mention that the refrigerant coil in each fan box is in series with the coil placed in each of the other three fan boxes used in this size unit cooling system. The refrigerant pipe enters through the small hole in the top of the fan box. It then is formed into a coil, as previously described, and then leaves through the small opening in the opposite side of the fan box top. From there it is run over to the next nearest fan box and the same treatment repeated, then on to the third and then the fourth fan boxes, each time repeating as in fan box number one. From the last fan box, the coil pipe then returns the refrigerant over the shortest route to the compressor so that it may be re-cooled and again re-circulated.

When the apparatus is used for heating purposes, the refrigerating coils are removed 120

and heating coils or other heating means substituted therefor, so that the air discharged from the boxes will be heated instead of cooled.

If an installation of this cooling system is made where there is no accommodating back room, a partition for placing exhaust fans, or in case for any reason the exhaust fans were objectionable, such as in a home, a church or a theatre, then this air washing, air cooling and air heating system can be made just as efficient and satisfactory in operation by connecting the fan boxes into the air ducts near the cooling cylinder. There the boxes could accommodate the baffles or dryer trays and also the cooling or heating coils with the same effectual results, satisfactory compensation could be obtained for discarding the four exhaust fans by increasing the size of the large fan placed at the rear of the cooling cylinder and thereby obtaining the same washing and drying efficiency, as well as the same hot or cold temperatures and also the same velocity of air and the same number of cubic feet per minute of conditioned air. Ornamental grilles could then be placed over openings wherever the ducts directed the conditioned air to enter the room receiving the conditioned air.

From an operation of a plant constructed in accordance with this invention and operated over a period of days during a hot spell in southern California, the following facts and figures are given:—

The large 30 inch fan at the rear of the cooling cylinder revolves 710 revolutions per minute, displacing 7500 cubic feet of air per minute; this air is blown through the cooling cylinder in which are ten water sprays which spray 30 gallons of water per minute, the same water being used over and over again and by this process, the water rapidly lowers in temperature until it reaches and stays around 60 degrees. The air blown into the cylinder at 100 degrees above zero has been cooled by the water 30 degrees while passing through the cooling cylinder. The evaporation of water from the supply tank is but thirty gallons per ten hours. In other words, 30 gallons of water, continuously pumped and repumped at the rate of 30 gallons per minute, cools the air passing through the cylinder 30 degrees, with the air velocity being such that 7500 cubic feet of air per minute is cooled 30 degrees lower than when it enters the cooling cylinder and when the outside air entering the cylinder has a temperature greater than 100 degrees, then the cooling process lowers the air temperature passing through the cylinder to around 35 degrees colder than when the air first entered the cylinder. This cooling of the air is accomplished without the aid of refrigeration or artificial cooling of any kind other than water. The cooled air is continually passing through the cooling cyl-

inder at the rate of 7500 C. F. M. and is blown into the room after first passing through ducts and then into exhaust fan boxes, from which fan boxes the air is exhausted into the room at the rate of 7500 C. F. M. The degree of coolness of the air blown into the room for cooling purposes can be regulated by adjusting the amount of water or the amount of air passing into and through the cooling cylinder. Before the washed and cooled air enters the fan boxes, it has to pass through baffle or dryer trays, which trays separate and retain from the air any surplus or over amount of moisture retained by the cooled air up to this point. Should the outside air be warm and damp, causing excess relative humidity to form in the room, artificially cooled, then the air passing into the fan boxes is further dried by blowing over refrigerant coils, but with this system of washing and cooling the air, the refrigerant coils are seldom needed to function for the purpose of more completely drying the cooled air and in case of refrigeration, the plant used is small. Not over a 50 pound per hour ice machine is required for this purpose, although other plants of this nature require around five tons refrigeration per day in order to wash, cool and dry 7500 C. F. M. which is the amount of air this plant handles per minute. After the air has passed over the refrigeration coils and regardless as to whether or not the coils are acting as a refrigerant, the exhaust fans which follow immediately in front of the refrigerant coils, pick up the air and exhaust it out of the fan boxes into the room to be cooled. These four fans, one in each of the four fan boxes, are 16 inch blade exhaust fans and the combined rating of the four exhaust fans is 6000 C. F. M., but the extra push and pressure created by the large fan in the rear of the cooling cylinder permits these four front exhaust fans to exhaust 7500 C. F. M. when running full speed. When these four front fans have their speed cut in half, they exhaust 5000 C. F. M. and when their current is entirely shut off, they still revolve at about one-third speed from the air pressure delivered to them from the large fan in the rear of the cylinder and then the cooled air blown into the room being cooled is at the rate of 3750 C. F. M., which gives three different volumes of air from the one cooling unit. Then again, the less air passing through per minute, lowers the temperature of the cooled air to a greater extent and which can then be again corrected if necessary by turning off one or more of the water sprays in the cooling cylinder.

It is thought from the foregoing description that the advantages and novel features of the invention will be readily apparent.

It is to be understood that changes may be made in the construction and in the combination and arrangement of the several parts,

provided that such changes fall within the scope of the appended claims.

What I claim is:—

1. An apparatus of the class described comprising a cylinder, means for forcing air into one end of the cylinder, discharge means connected with the other end of the cylinder, such means including an exhaust fan, means for spraying water into the air current as it passes through the cylinder, means for using the water over and over again and cooling fins in the cylinder for receiving the water sprayed from the spraying means.

15 2. An apparatus of the class described comprising a cylinder having one end open and its other end closed, a motor driven fan for forcing air into the open end, fan boxes in communication with the closed end, a 20 motor driven fan in each box, water spray heads in the cylinder for spraying the air current passing through the same, a tank for receiving the water draining from the cylinder, a motor driven pump for taking the water from the tank and delivering it 25 to the heads and cooling fins in the cylinder against which the water from the heads strike.

3. An apparatus of the class described comprising a cylinder having one end open and its other end closed, a motor driven fan for forcing air into the open end, fan boxes in communication with the closed end, a motor driven fan in each box, water spray 35 heads in the cylinder for spraying the air current passing through the same, a tank for receiving the water draining from the cylinder, a motor driven pump for taking the water from the tank and delivering it to the heads, cooling fins in the cylinder against which the water from the heads strike and baffles in the fan boxes in rear of the fans for removing surplus water from the air.

4. An apparatus of the class described comprising a cylinder having one end open and its other end closed, a motor driven fan for forcing air into the open end, fan boxes in communication with the closed end, a motor driven fan in each box, water spray 50 heads in the cylinder for spraying the air current passing through the same, a tank for receiving the water draining from the cylinder, a motor driven pump for taking the water from the tank and delivering it to the heads, cooling fins in the cylinder against which the water from the heads strike, baffles in the fan boxes in rear of the fans for removing surplus water from the air and means in the fan boxes for changing the temperature of the air.

5. An apparatus of the class described comprising a cylinder, a motor driven fan for forcing air into one end of the cylinder, pipes connected with the other end of the cylinder, boxes into which the pipes deliver

the air, a discharge fan in each box, baffles in each box, spray heads in the cylinder for spraying the air passing through the same, a pump for forcing water to the heads, a tank for receiving the water draining from the cylinder and to which the inlet of the pump is connected, fin supporting means in the cylinder and spaced from the same, each of such means receiving the water from a head whereby noise of the spray water striking the cylinder is eliminated and the fins cool the water, the top of the cylinder having openings therein and removable frames covering the openings and provided with transparent portions.

6. An apparatus of the class described comprising a cylinder, means for forcing air into the same, means for spraying the air current passing through the cylinder with a liquid, a discharge box for receiving the air from the cylinder, a discharge fan in said box, removable trays in said box, V-shaped baffle plates in each tray and a refrigerating coil in said box in front of the trays.

In testimony whereof I affix my signature. 90
GUY F. KELLEY.
